UNITED STATES PATENT OFFICE

WALKER W. McCARROLL, OF NEW HAVEN, CONNECTICUT

MACHINE FOR RECTIFYING ELECTROTYPEs

Application filed May 26, 1928. Serial No. 280,810.

This invention relates to machines for rectifying electrotype and more particularly pertains to improvements upon my Patents Nos. 1,109,855 and 1,109,856 both issued September 8, 1914, and No. 1,112,544 issued October 6, 1914.

The present invention has for one of its objects an improved mechanism for actuating the glass block during the hammer operation and to likewise provide improved mechanism for actuating the hammer.

Further the invention aims to provide improved means for effecting simultaneous control of the glass block and hammer operating mechanisms.

Another object of the invention is to provide improved means for initially forcing the tool against the plate and thereby the latter against the glass block, prior to the hammer entering into operation, thereby requiring less hammering force and minimizing injury to the plate.

A still further object of the invention is to provide improved means for shifting the glass block and the tool holder and for also effecting vertical adjustments of the glass block in accordance with electrotype of varying thicknesses, and for further safeguarding the glass block against injury.

The invention also generally aims to provide a more efficient machine of this type which is of certain and positive operation, which can be more easily and quickly operated, and which can be controlled by the operator with minimum effort so as to not detract from concentration on the work.

The invention has still further and other objects hereinafter set forth and manifested in the course of the following description.

In the drawings:

Fig. 1 is a perspective view of the invention;

Fig. 2 is an enlarged partial front elevation;

Fig. 3 is an end elevation;

Fig. 4 is a side elevation of the hammer operating mechanism;

Fig. 5 is a detail view in top plan and partial section of the glass block;

Fig. 6 is a sectional view of a portion of the tool block or holder;

Fig. 7 is a section on line 7—7 of Fig. 6;

Fig. 8 is a side elevation, partially in section, of the glass block adjusting mechanism;

Fig. 9 is a section on line 9—9 of Fig. 8;

Fig. 10 is a section on line 10—10 of Fig. 4;

Fig. 11 is a detail view of the washer of Figs. 6 and 7;

Fig. 12 is a detail view in top plan of the means for shifting the glass block; and

Fig. 13 is a detail side elevation of the means for adjusting the glass block and the tool carrier.

In proceeding in accordance with the present invention, a main frame 1 is employed having a bed 2 upon which an inverted U-shaped frame 3 is mounted. The horizontal portion or top of the frame 3 is provided with a bearing 4 in which latter the lower end 70 of a vertical interiorly threaded sleeve 5 is slidable. The upper end of the sleeve is likewise slidable in a bearing 6 formed in the upper end of a substantially Z-shaped bracket 7 that is bolted onto the top of frame 3. A vertical shaft 8 is threaded through the sleeve 5 and has a hand-wheel 9 fixedly secured thereto at its upper end by means of a pin 10 which passes through the shaft and through a weight 11 that forms the hub of the wheel. 80

Downward movement of the shaft is limited by a stop member 12 in the form of a bolt adjustably threaded into engagement with the top of bracket 7, and which is held in adjusted position by a lock-nut 13. The head of the bolt 12 is, as shown in Fig. 1, engageable with the under face of the weight 11. A lock-nut 14 is provided for the shaft 8 and has a handle 15 connected thereto for convenience in operation. 90

The lower end of the shaft 8 is provided with a circular head 16 which engages with a boss 17 formed on a sleeve 18. A hollow nut 19 is perforated to receive shaft 8 and is threaded over the boss 17 and is held in place by a lock-nut 20. The sleeve has a pointer 21 secured to and depending therefrom and slidably receives a horizontal cross-bar 22. The cross-bar is secured at its ends to spaced vertical posts 23, the latter being formed to re- 100

ceive and being slidable on studs 25 that are rigidly secured to a slide 24. The slide is mounted in a dovetail guide 26 that is rigidly affixed to the under side of the top of frame 3.

5 A circular glass block 27 is removably mounted in a holder composed of a lower member 28 and an upper member 29, between which members the block is clampingly held through the medium of bolts 30. The upper member 29 is provided with opposed wings 31 to the upper faces of which are secured by bolts 32 the bases of bearing members 33, the latter being provided with spaced perforated ears 34 to receive trunnions 35 projecting outwardly from opposite sides of the lower ends of the posts 23.

10 For the purpose of leveling the glass block, a bar 36 is disposed transversely across and above the glass block holder and has adjusting screws 37 at its ends which bear upon the holder and are secured in adjusted position by means of lock-nuts 38. A threaded stem 39 is rigidly secured to the leveling bar 36 and projects upwardly therefrom and slidably through guide ears 40 formed on the adjacent post 23. For the purpose of holding the screws 37 firmly against the glass block holder, a spring 41 is employed which encircles the stem 39 and at one end bears against the upper ear 40, while its opposite end bears against a nut 42 adjustable on the stem. By adjustment of the nut the pressure of the leveling bar on the glass block holder can be varied as desired.

15 The glass block 27 is provided with indexes 43 on its lower face which are of varying forms and which are in registry with tools of corresponding forms, in accordance with the nature of the required rectification of the electrolyte. Therefore in order to bring the desired tool into registry with the pointer, the tools and also the glass block holder are slidable along the bed, and accordingly a rod 44 is secured at one end to the slide 24 and has its opposite end extending through an aperture 45 provided therefor in the adjacent leg 60 of frame 3 and secured to the upper end of a vertical connecting bar 46. The lower end of bar 46 is secured to a rod 47 (Fig. 2) which is also slidable through the adjacent leg 60 of frame 3. A bracket 49 is secured to the said leg of frame 3 and has a quadrant 50 formed with spaced holes to receive a spring-pressed latching pin 51 operated by a lever 52 which latter is pivoted at 53 to an end of a hand-lever 54, the lever 54 being pivoted at 55 to the bracket. A pin 56 connects the lever 54 to the bar 46 so as to slide same and therewith the rods 44 and 47. A guide rod 57 is secured to the cross-bar 46 and operates through an opening provided therefor in said leg 60 of the frame.

20 A lever 75 is pivoted by means of a link 76 adjacent its front end to the top of frame 3, and has its said front end bifurcated and

pivoted at 77 to an enlarged portion 78 formed on the sleeve 5 intermediate the ends of the latter. The outer or rear end of the lever 75 extends through a guide or yoke 79 secured to the frame 3. A rod 80 has the upper end thereof extending through a perforation formed in the rear end of the lever 75 and is provided with a nut 81 against which the under face of the lever is held by a coil spring 82 mounted on the rod and seated on the upper face of the lever and against a nut 83 adjustable on the rod. The frame 3 is formed with an extension 84 which is perforated to receive the rod 80 so as to provide a guide for the rod. The intermediate portion of the rod 80 has a yoke 85 rigidly secured thereto, the yoke slidably embracing a rod 86 parallel to rod 80. A stop and a lock-nut 87 are adjustable on rod 86, the stop nut engaging the top of the yoke. The upper end of rod 86 also extends through a guiding aperture provided therefor in extension 84 of frame 3, and has a coil spring 88 thereon which latter at one end abuts the under face of extension 84 and at its opposite end seats on a stop nut 89.

25 A yoke 90 is fixedly secured to rod 86 by means of a taper pin or screw 91 and has a roller 92 journaled thereon, the yoke slidably embracing the rod 80. A control block 93 is fixedly secured by a taper pin or screw 94 to rod 80 and has a foot provided with an adjustment screw 95, the latter equipped with a lock-nut. The screw 95 is employed to adjust an L-shaped slide 96 carried by the block, the slide being engageable with a locking arm 97 and with its adjustment screw 98. The locking arm is secured to a shaft 99 journaled in the frame 1.

30 A coil spring 100 encircles the rod 80 and at one end engages yoke 85 while its opposite end presses downwardly on yoke 90, thereby holding the roller 92 of the yoke against a cam 101 mounted on a shaft 102. A connecting rod 102' is pivoted to the cam 101 and is driven by an eccentric 103 on a main drive shaft 104. The shaft 104 has a pulley 105 thereon which is driven by a belt 106 that in turn is driven by a pulley 107 mounted on shaft 102. A motor 108 has a pulley 109 on its armature shaft which through the belt 110 drives a pulley 111 on shaft 102.

35 A blower pump 112 has a driving pulley 113 which is driven by a belt 114 from a pulley 115 on shaft 102. An air conduit 116 extends upwardly from the blower and has a horizontal branch 117 which slidably telescopes with a pipe 118 that has a depending branch 119. The free or lower end of branch 119 is equipped with a nozzle 120 overlying the bed.

40 A turnbuckle 121 is pivotally connected at one end to a lug 122 on the control block 93 while its opposite end is pivoted to the outer end of a lever 123 which latter in turn is piv-

oted at 124 between its ends to and beneath the bed 2. A second lever 125 is pivoted between its ends at 126 to and beneath the bed and is connected at its inner end to the adjacent end of the lever 123 by a pin 127 pivoted at 128 to lever 125 and having a spring 129 adjustably held against lever 123 by nuts 130. The forward end of the lever 125 is secured to a hammer or hammer head 131' by means of nuts 132. A hammer collar 133 is adjustably threaded on rod 131 and held thereon by a nut 134. Rod 131 is guided in its vertical reciprocatory movements by brackets 135 and 136 on the frame 1 and is tensioned by means of a main or heavy spring 137 which surrounds a thimble 138 on the rod, the spring seating on the bracket 136 and bearing against nuts 139 on the rod 131. A spring 140 lighter than the spring 137 surrounds a thimble 142 on the rod 131 and extends within a second thimble 138, and abuts nuts 141 threaded on the rod. The lighter spring 137 counterbalances the weight of the hammer and imparts a light stroke thereto.

20 A hammer actuating rod 143 is operated by a cam 144 on the shaft 104 and is provided with a tripper 145, the upper end of the rod being guided in a sleeve 161 carried by a guide 160. The tripper is provided with an adjustable bit 175, which is engageable with the hammer collar 133.

25 A vertical tripper rod 146 is guided by the brackets 135 and 136 and has a fitting 147 thereon, to which latter a treadle rod 147' is pivoted at 148. A rod 149 is pivoted at one end at 150 to the opposite end of the fitting 147 and is pivoted at its opposite end at 151 to an arm 152 mounted on the horizontal shaft 99. A foot treadle 153 is connected to the lower end of rod 147' and is pivotally mounted at its rear on a rod 153' that is carried by brackets 153''.

30 A bracket 154 is fixed to the upper end of rod 146 and has a roller 155 journaled thereon, which latter is adapted to be engaged by a cam slide 156 fixedly mounted on the rod 143.

The cam slide 156 is tensioned by means of a pair of springs 157 mounted on rods 158 and 35 abutting a bracket 158'. Nuts 159 on the outer ends of the rods abut the bracket and enable adjustment of the position of the cam 156 with respect to roller 155. The inner ends of the rods are connected to cam slide 156 and slidably pass through guide 160 which latter is pivoted at 174 to sleeve 161.

40 The tool holder is composed of a block 157 slidable in the work bed 166 which has bores wherein the stems or shanks 158 of the variously shaped tools 164 are slidably mounted. The stems are provided with fixed thimbles 159 encircled by coil springs 160, the latter at one end abutting the upper half 161 of the holder and at their opposite ends being 45 spaced from horseshoe shaped or split wash-

ers 162, which latter are mounted in countersunk parts 163 provided therefor in the lower half of the holder.

The thimbles thus restrict upward movement of the tools and thereby prevent the tools from contacting with the glass block in case of negligence on the part of the operator. A slide 165 is, as shown in Fig. 1, mounted in a guideway provided therefor in the work table or bed 166 and moves with the tool holder or block, being fastened thereto at 167.

In operation the belt 110 which is driven by the motor 108 effects continuous drive of the shaft 102 and the latter through the belt 106 effects continuous drive of the shaft 104. The cam 101 is continuously oscillated by the connecting rod 102' connected to the cam 102 of shaft 104, and through the roller 92 and the yoke causes constant reciprocation of the rod 86. Normally the latch 97 is engaged with the control block 93 and thereby holds rod 80 in the depressed position of Fig. 3. Referring now to Fig. 4, it will be noted that the rod 143 carrying the tripper 145 is also continuously reciprocated by the cam 144 from the shaft 104. Thus it will be noted that both the rods 86 and 143 are being continuously reciprocated. When a plate is to be rectified, the foot treadle 153 is depressed, which causes the rod 147' in Fig. 4 to be depressed and through rod 149 connected thereto by fitting 147, the shaft 99 will be rocked by its arm 152, and since as shown in Fig. 3 the latch 97 is connected to the shaft 99, the latch will be disengaged from the control block 93 and the latter moving upwardly by the action of the cam 101 compresses the spring 100 and through the yoke 85 causes upward movement of the rod 80.

When the roller 92 moves downwardly on the low side of the cam, the spring 88 which has been compressed by the upward movement of rod 86 then presses downwardly on the nut 89 and through the yoke 85 causes downward movement of the rod 80. The rod 80 is thus reciprocated and by virtue of being connected to the lever 75 effects vertical reciprocation of the sleeve 5, Fig. 8, and through the shaft 8 causes the bar 22 to vertically reciprocate the glass block 27 through the medium of the posts 23, which slide on the studs 25. Thus the glass block is given a vertical reciprocal motion. Referring to Fig. 2 and Fig. 3, it will be noted that the upward movement of the control block 93 causes similar movement of the turnbuckle 121 and the latter being connected to the outer end of lever 123 raises said end thereby depressing the opposite end of the lever and through the spring device 129 depresses the inner end of lever 125 and raises the outer end of the latter lever, which is connected to the hammer 131'. The timing is such that the hammer is caused to engage the tool, thereby causing the latter to engage the work prior

to reciprocation of the hammer. Referring to Fig. 4, it will be noted that the downward movement of the rod 147 through the fitting 147 effects downward movement of the rod 146 which carries the roller 155 connected to rod 146 downwardly, and the spring device 157 entering into action forces the cam 156 inwardly, thereby moving the bit 175 of the tripper 145 into engagement with the hammer collar 133 thereby depressing the latter and the hammer rod 131 against the action of its springs 137 and 142. On the downward movement of the rod 143, the roller 155 riding on the cam 156 moves the cam and thereby the rod 143 away from the collar 133 so as to disengage the bit 175 from the collar, whereupon the energy stored up in the said springs causes the hammer to deliver its blow to the tool.

When the treadle is released, same moves the rod 147 upwardly thereby rocking the shaft 99 to reciprocate the latch 97 to the operative position of Fig. 3, in which position the latch holds the rod 80 depressed and inactive, and likewise restores the roller 155 to the position of Fig. 4, in which the hammer operating means is likewise rendered inactive.

From the foregoing, it will be noted that the rod 80 which actuates not only the lever 75 which reciprocates the glass block, but also the levers 123 and 125 for moving the hammer head 131 against the tool, is normally inactive, as is also the means of the hammer 131 for causing same to deliver its blow, while the rod 86 which upon release of the latch 97 operates the rod 80, is continuously active, as is also the rod 143 which actuates the hammer blow delivering means.

Referring to Figs. 6 and 7, it will be seen that due to the thimbles 159 operative movement of the tools against the work is restricted, the limit of movement being such so that the tools cannot come in contact with the glass block when the stop member 12 is set properly.

It will further be noted that by release of the lock-nut 14, the rod 8 can be rotated by the hand wheel 9 to move the glass block in operative relation to the work in accordance with the thickness of the latter, and by manipulation of the lever 54, the cross member 46 through the rod 44 will move the slide 24 and therewith the glass block and also the tool block to cause the desired tool 164 to register with the indexes 43 on the lower face of the glass block, as set forth in my said prior patents.

It will also be noted that the lever 125 normally presses down on the hammer rod 131 so as to assist in tensioning the latter.

What is claimed is:—

1. In combination with a glass block, a tool and a hammer for actuating the tool, a pair of pivoted levers, a resilient connection between the levers, a hammer head connected

to one of the levers, means to initially operate said levers thereby to move the tool against the work so as to hold the latter against the glass block, and means to subsequently reciprocate the hammer.

2. In combination with a vertically reciprocal glass block, a lever mechanism pivotally connected to the block, a spring tensioned reciprocal rod connected to the lever mechanism, a second spring tensioned reciprocal rod, means connected to the second rod to reciprocate same and to tension the spring of the first rod, and means connected to the first rod to tension the spring of the second rod.

3. In combination with a tool and a vertically reciprocal glass block, means having connection with the block to reciprocate same, means to actuate said reciprocating means, means to latch said actuating means against movement, a hammer normally inoperative, means to actuate the hammer, and means for simultaneously releasing the latch and for rendering said hammer actuating means operative.

4. In combination with a tool and a vertically reciprocal glass block, means having connection with the block to reciprocate same, means to actuate said reciprocating means, means to latch said actuating means against movement, a hammer normally inoperative, means to actuate the hammer, means to move the tool against the work and thereby the latter against the glass block, in advance of the hammer operation, and means for simultaneously releasing the latch and actuating said tool moving means and for then rendering the hammer actuating means operative.

5. In combination with a tool and a vertically reciprocal glass block, means to reciprocate the block, means connected to the hammer to move same against the tool thereby to cause the tool to force the work against the block, means to reciprocate the hammer, normally quiescent means connected to the block reciprocating means and to said means for moving the hammer against the tool to operate each, continuously operated means to drive said normally quiescent means, normally quiescent means to reciprocate the hammer, continuously operated means to drive said normally quiescent hammer reciprocating means, means to effect operation of each of the normally quiescent means from its driving means, and control means for simultaneously effecting said operation of each of the normally quiescent means.

6. In combination with a tool and a vertically reciprocal glass block, means to effect movement of one of said elements, and means to operate said first-named means including reciprocal means, means to constantly actuate said reciprocal means, a second reciprocal means connected to said first-named means, latching means for the second recip-

rocal means to normally render same inoperative, and means to effect operation of the second reciprocal means and thereby the first-named means upon release of the latching means.

7. In combination with a tool and a vertically reciprocal glass block, means to effect movement of one of said elements, and means to operate said first-named means including a reciprocal rod connected to said first-named means and having a spring thereon, a second reciprocal rod having a spring thereon, a member rigid on the second rod and engaged with the spring thereof and slidably connected to the first rod, an abutment on the first rod to engage the member, an arm rigid on the first rod and slidably connected to the second rod and engaged with a spring of the latter, means to constantly reciprocate the first rod, a control member rigid on the second rod, latching means for engaging the control member to hold the second rod depressed and with its spring under tension, and means to release the latching means.

8. In combination with a tool, a reciprocal glass block and a hammer, means to initially move the tool against the work, normally quiescent means to reciprocate the hammer, means having connection with the block and with said tool-moving means to actuate each, latching means for said block and tool actuating means to normally hold same inoperative, continuously driven means to actuate the hammer reciprocating means and the block and tool actuating means, a shaft connected to the latching means, means connected to the shaft to render the hammer reciprocating means operative, and foot-operated means to actuate the shaft thereby to release the latch and render the hammer reciprocating means operative.

9. In combination with a tool and a reciprocal glass block, means to actuate one of said elements including a reciprocal spring tensioned device, a second reciprocal spring tensioned device, means to effect constant reciprocation of the second device, means to releasably hold the first device against movement, and means to actuate the first device from the second device upon release of said holding means.

10. In combination with a tool and a reciprocal glass block, means to actuate one of said elements including a reciprocal spring tensioned device, a second reciprocal spring tensioned device, a rocking cam, means to rock the cam, means on the second device engageable with the cam to effect constant reciprocation of the second device, means to actuate the first device from the second device, and means to latch the first device against reciprocation without affecting said movement of the second device.

11. In a rectifying machine, a tool block having spaced upper and lower portions

formed with tool-receiving bores, tools reciprocal in the bores, thimbles on the tools disposed in said space between the portions of the block and having their upper ends engaged with the upper portion to limit upward movement of the tools, abutments spaced below the lower ends of the thimbles and carried by the tools to engage the lower ends of the thimbles, and springs surrounding the thimbles and engaged with the abutments and with the upper portion of the block.

12. In a rectifying machine, a tool block having spaced upper and lower portions formed with tool receiving bores, tools reciprocal in the bores, thimbles on the tools disposed in said space between the portions of the block and having their upper ends engaged with the upper portion to limit upward movement of the tools, shoulders on the tools, split members surrounding the tools and seated on the shoulders and spaced below the lower ends of the thimbles, the lower portion of the block having countersunk portions receiving the members, and springs surrounding the thimbles and engaged with the members and with the upper portion of the block.

13. In combination with a tool, a reciprocal hammer rod, a thimble surrounding the rod, means slidably supporting the lower end of the thimble, an abutment on the thimble, a spring surrounding the thimble and engaged with said abutment and supporting means, a collar on the hammer, a lighter spring surrounding the rod and engaged with the collar and extending through the thimble and seated on said supporting means, and means to depress the collar and thereby compress said springs and to release the collar.

14. In combination with a tool, a reciprocal hammer, a heavy spring device associated with the hammer to operate same to deliver a blow, a lighter spring device also associated with the hammer to operate same to deliver a blow, a lighter spring device also associated with the hammer to operate same and to counterbalance the weight of the hammer, and means to move the hammer against the tension of said devices and to then release same to cause the hammer to deliver its blow.

15. In combination with a tool, a reciprocal glass block, normally inactive means to move the tool against the work and to reciprocate the glass block, continuously moving means to actuate the first-named means, normally inactive means to deliver blows to the tool, continuously moving means to actuate the blow delivery means, a rocking shaft, manually controlled means to rock the shaft, means connected to the shaft for releasably holding the first-named means inactive, means also connected to the shaft for releasably holding the blow delivery means inactive, and means operable upon releasing movement of the shaft for effecting operation of each

of the normally inactive means from its said actuating means.

16. In combination with a tool and a hammer therefor, a lever device controlling the hammer, and means to actuate the lever device thereby to initially cause the hammer to lightly engage the tool and the latter to engage the work, and means to subsequently operate the hammer.

17. In combination with a tool and a hammer and a glass block, means to move the hammer into light engagement with the tool, means to actuate said first-named means having a vertically reciprocal part, means to releasably hold said part depressed, and means which upon release of said holding means effects upward movement of the hammer moving means to engage and move the tool against the work.

18. In combination with a tool and a hammer and a glass block, lever means controlling the hammer to move the hammer upwardly against the work, means to actuate the lever means including a spring tensioned element, means to connect the lever means to said element, and means to normally hold said element depressed against the action of its spring and which upon release enables the element to move upwardly under the action of its spring thereby to actuate the lever means to move the hammer against the tool and the tool against the work.

19. In a rectifying machine, a frame, a glass block holding means, a vertical threaded rod, a sleeve through which the rod is threaded, means to mount the sleeve for vertical reciprocal movement in the frame, means connected to the sleeve to reciprocate same, means to turnably connect the rod to the holding means of the glass block, and means of lock the sleeve and rod in their adjusted relation.

20. In a rectifying machine, a frame, a glass block holding means, a vertically reciprocal member carried by the frame, means to adjustably connect the holding means to the said member, and means to reciprocate said member.

In testimony whereof I affix my signature.
50 WALKER W. McCARROLL.
